FIG. 7

UNITED STATES PATENT OFFICE

2,144,810

ADJUSTING DEVICE FOR JARS

Edward F. Raymond, Los Angeles, Calif., assignor,
by mesne assignments, to James A. Kammer-
diner, Los Angeles, Calif.

Application April 27, 1935; Serial No. 18,605

13 Claims. (Cl. 255—27)

This invention relates to improvements in adjusting devices for straight pull jars, such as employed in fishing operations during the drilling of an oil well.

5 The general object of this invention is to provide an adjusting device for use in a straight pull jar which device includes yieldable detention means and a coacting arbor member for adjusting the position of the detention means relative 10 to the arbor member.

Another object of the invention is to provide means for adjusting the relative positions of the detention means and the arbor without removing the tool string or jar from the well.

15 Other objects and the advantages of this invention will be apparent from the following description taken in connection with the accompanying drawings, wherein:

Fig. 1 is a fragmentary longitudinal section 20 through a drill string showing a jar release device and my improved adjusting means.

Fig. 2 is a view similar to Fig. 1 showing the device in another position.

Fig. 3 is a view similar to Fig. 2 showing the device in still another position.

Fig. 4 is a fragmentary enlarged detail of the adjusting device partly in section.

Fig. 5 is a section taken on line 5—5 of Fig. 4.

Fig. 6 is an enlarged fragmentary detail of the 30 adjusting device.

Fig. 7 is an enlarged fragmentary longitudinal section through the adjusting device.

Fig. 8 is a view similar to Fig. 7 showing a different portion of the device.

35 Fig. 9 is a section taken on line 9—9 of Fig. 7.

Fig. 10 is a section taken on line 10—10 of Fig. 7, and

Fig. 11 is a detail view of the jar detention means or slip.

40 Referring to the drawings by reference characters I have indicated a drilling string generally at 10. As shown the drill string 10 includes a jar release device 12 and my improved adjusting device which is indicated generally at 13.

45 The jar release device 12 is of a standard type which includes a body 14 having a bore 15 therein in which an arbor 16 is positioned. The jar release device 12 further includes a detention means or slip device 17 positioned in the bore 15 and surrounding the arbor 16. The body 14 is connected to a member 14a which has a shoulder 14b thereon and which is adapted to be brought into hammering engagement with a shoulder 14c on the arbor 16 as shown in Fig. 8

55 of the drawings. The slip 17 includes a plurality

of inwardly formed shoulders 18 which are adapted to engage shoulders 19 on the arbor 16 to prevent free longitudinal movement of the arbor. (See Fig. 2.) The slip 17 includes a plurality of slits 20 to make it resilient to allow the arbor shoulders 19 to pass the slip shoulders 18.

The bore 15 includes a threaded portion 21 which is engaged by a nut member 22 surrounding the arbor 16 and on which the slip 17 rests. The nut 22 includes a plurality of upstanding lugs 23 (see Fig. 8) which fit in recesses 24 in the slip to lock the slip and the nut for rotative movement together. Adjacent the top of the body 14 the bore 15 includes a threaded portion 25.

My improved adjusting device 13 includes a body portion 26, a coupling member 27 and a sub-member 28. The body portion 26 includes a reduced externally threaded portion 29 by means of which it is threadedly secured to a string of standard drill pipe as indicated at 30.

Opening through its lower end the body 26 has a recess 31 therein and the lower end of the body is formed to provide a plurality of spaced depending teeth members 32 (see Fig. 6). Extending upward from the recess 31 the body 26 includes a reduced splined recess 33 and extending upward from the splined recess 33 the body 26 includes a reduced aperture 34 having a threaded portion 35 adjacent its lower end and a threaded portion 36 adjacent its upper end.

Adjacent the lower end of the body above the teeth 32 the recess 31 includes a threaded section as indicated at 37.

Positioned in the recess 31 of the body 26 I provide a slide member 38 the lower end of which is formed to provide a plurality of spaced teeth members 39 (see Fig. 4). Opening through the lower end thereof the slide member 38 includes a threaded recess 40 and extending upward from the recess 40 the slide member has a reduced aperture 41 therein.

Positioned in the recess 31 of the body 26 I provide a collar member 42 which is externally threaded as indicated at 43 to engage the threads 37 of the body 26. The lower end of the collar member 42 terminates adjacent the roots of the body teeth 32 and above the threads 43 the collar is formed to provide a plurality of upwardly extending teeth 44 which are adapted to mesh with the teeth 39 of the slide member 38. Furthermore, the collar 42 has a coaxial aperture 45 therethrough as clearly shown in Fig. 7.

The coupling member 27 includes a body portion 46 having a reduced depending externally threaded hub portion 47 and a reduced upwardly

extending stem portion 48. The coupling body 46 further includes a plurality of upwardly extending teeth 49 surrounding the stem portion 48 which are adapted to mesh with the teeth 32 of the body 26. The coupling stem 48 is positioned in the aperture 45 of the collar member 42 and adjacent its upper end includes an externally threaded portion 50 which is positioned in the threaded recess 40 of the slide member 38. Furthermore, the coupling member 27 has a coaxial aperture 51 therethrough.

The submember 28 adjacent its lower end includes a reduced externally threaded boss 52 and adjacent its upper end includes a threaded recess 53. Extending throughout its length the submember 28 has a coaxial aperture 54 therein. The threaded boss 52 of the submember 27 engages the threads 25 of the jar release device 12 and the threaded hub 47 of the coupling member 27 engages the threaded portion 53 of the submember 28.

Positioned in the aperture 54 of the submember 28 I provide a sleeve member 55 the lower end of which extends into the bore 15 of the jar release device 12 where it includes an enlarged head portion 56. The sleeve member 55 extends upward through the aperture 51 of the coupling member, through the aperture 41 of the slide member 38 and into the aperture 33 of the body 26 where it includes an enlarged splined head 57 which meshes with the splines of the splined body recess 33. (See Fig. 9.) Where the sleeve 55 is positioned in the threaded aperture 41 of the slide member 38 it includes an enlarged externally threaded portion 58 which engages the threads of the aperture 41. Opening through the bottom thereof the sleeve head 56 has a recess 59 therein and extending upward from the recess 59 the sleeve has a coaxial aperture 60 therein. The sleeve head 56 further includes a plurality of depending lugs 61 (see Fig. 8) which fit into a plurality of recesses 61' in the upper face of the jar slip member 17. Positioned in the aperture 60 of the sleeve member 55 I provide a flush pipe 62 the lower end of which is suitably secured to the jar arbor 16 as indicated at 63. The flush pipe 62 extends upward out of the sleeve member and out of the body 26 through the aperture 34 therein. Surrounding the flush pipe 62 in the aperture 34 I provide suitable packing material 63 which is held between nuts 64 and 65.

When my improved adjusting device 13 and its associated jar release device 12 are operatively installed in a drill string during a drilling operation and the drill bit becomes jammed thereby necessitating jarring to release it the driller pulls the drill string upward until the jar release device releases to deliver a blow. If the driller thinks the blow too light or the strain on the pipe too great he may vary the intensity of the next blow by adjusting the relative relation of the slip 17 and the arbor 16. To adjust the slip the driller resets the jar release device 12 and then raises the drill string to a height where the body teeth 32 disengage the coupling teeth 49 and the collar teeth 44 do not engage the slide teeth 39 as shown in Fig. 2.

The driller then rotates the drill string and the body member 26, through the medium of the splined connection, with the sleeve 55 rotates the sleeve. As the sleeve 55 is thus rotated the threads 58 raise or lower the sleeve depending on the direction of rotation. When the sleeve 55 is rotated the head lugs 61 thereof rotate the

slip member 17 which in turn through the lugs 23 rotates the collar member 22. As the collar member 22 is thus rotated the threads thereof cause it to raise or lower depending on the direction of rotation. As the collar 22 moves it moves the slip 17 either up or down thereby changing its position relative to the arbor 16. Thereafter the driller raises the drill string until the collar teeth 44 mesh with the slide teeth 39 thereby through the medium of the coupling item 48 again rotatively connecting the body 26 to the coupling member 27. Thereafter torque tension may be applied to the jammed bit as the drill string is pulled upward to trip the jar release device.

To prevent accidental turning of the sleeve member 55 I provide a plurality of latch members which are indicated at 66 in the coupling member 27. (See Figs. 7 and 10.)

As shown the body 46 of the coupling member has a pair of opposed apertures 67 therein with threaded portions 68 adjacent their outer ends in each of which a threaded plug 69 is positioned. Each of the threaded plugs 69 has an aperture 70 therein in which a stem 71 is positioned. The stem 71 includes an enlarged pointed two-way latch head 72. Surrounding the stem 71 between the head 72 and the plug 69 I provide a coiled spring 73 which resiliently urges the latch head towards the sleeve 55. Adjacent the latch members 66 the sleeve has a plurality of tapered sided slots 74 therein into which the springs 73 urge the latch heads 72. When the driller intentionally rotates the sleeve 55 as previously described he applies sufficient torque to cause the latch heads 72 to be forced out of the slots 74.

At 75 in the submember 28 I have shown another set of latch members similar to the latch members 66 which may be set so that the latch heads thereof are out of the sleeve slots 74 when the latch heads of the members 66 are in the sleeve slots 74.

From the foregoing description it will be apparent that I have provided a novel adjusting device for straight pull jars which is simple in construction and highly efficient in use.

Having thus described my invention I claim:

1. In combination of a string of drill pipe, a jar release device including a housing having an arbor and a movable arbor detention device 50 therein and an adjusting device movable in said housing, said adjusting device including an upper portion and a lower portion, means connecting said upper portion and said drill pipe, means connecting said lower portion and said jar housing, clutch means connecting said upper and lower portions of said adjusting device for rotative movement, said adjusting device including means operable upon disengagement of said clutch means and upon rotation of said drill pipe 60 to move said detention device axially in said jar housing, said adjusting device including a second clutch means for rotatively connecting said two portions thereof, said second clutch means being operable into engagement after said first clutch 65 means has been disengaged and said drill pipe moved upward a predetermined distance.

2. The combination of a string of drill pipe, a jar release device including a housing having an arbor and an arbor detention device therein and 70 an adjusting device including movable upper and lower portions, means connecting said upper portion and said drill pipe and means connecting said lower portion and said jar housing, toothed clutch means connecting said upper and lower 75

portions, said upper portion having a recess therein opening through the bottom thereof, said upper portion having a reduced splined recess therein opening into said first recess, said upper portion having a reduced aperture therein opening into said splined recess and through the upper end of said upper portion, a collar member positioned in said first recess adjacent the lower end thereof and secured to said upper portion, said collar including an upwardly directed toothed clutch portion, said collar member having an aperture therethrough, said lower portion of said adjusting device including an upwardly extending reduced stem portion, said stem being positioned in said collar aperture and in said first recess, said stem having a downwardly directed toothed clutch portion thereon in said first recess adapted to mesh with said clutch portion of said collar, said lower portion including said stem having an aperture therethrough, a sleeve member positioned in said lower portion aperture and extending upward into said splined aperture of said upper portion, said stem including an enlarged splined head engaging the splines of said splined aperture, the lower portion of said sleeve extending into said jar housing and including means engaging said detention device for relative rotation, said toothed clutch portions of said stem portion of stem and said collar member being out of engagement when said toothed clutch portions of said upper and lower portions are in engagement, said sleeve member being rotatable with said upper portion and relative to said lower portion when both of said sets of toothed clutch portions are out of engagement and being rotatable with said upper and lower portions when said toothed clutch portion of said collar has been raised to mesh with said toothed clutch portion of said stem.

3. The combination of a string of drill pipe, a jar release device including a housing having an arbor and an arbor detention device threaded therein and an adjusting device including an upper and a lower portion connected to said drill pipe and said jar housing, respectively, clutch means connecting said portions, said upper portion having a recess therein opening through the bottom thereof and having a reduced splined recess therein opening into said first recess, said upper portion having a reduced aperture therein opening into said splined recess and through the upper end of said upper portion, a collar member positioned in said first recess adjacent the lower end thereof and secured to said upper portion, said collar including a clutch portion, said collar member having an aperture therethrough, a slide member positioned in said first recess of said upper portion, said slide member including a clutch portion coating with said last mentioned clutch portion, said slide member having a threaded aperture therein, said lower portion of said adjusting device including an upwardly extending reduced stem portion positioned in said collar aperture, means connecting the upper end of said stem and said slide member, said lower portion including said stem having an aperture therethrough, a sleeve member positioned in said lower portion aperture and extending upward through said threaded aperture of said slide and into said upper portion, said stem including an enlarged splined head engaging the splines of said splined aperture and an enlarged threaded portion engaging the threads of said threaded aperture of said slide member, the lower portion of said sleeve extending into said jar housing and

including means engaging said detention device for relative rotation, said clutch portions of said slide member and said collar member being out of engagement when said clutch portions of said upper and lower portions are in engagement, said sleeve member being rotatable with said upper portion and relative to said lower portion when both of said sets of clutch portions are out of engagement and being rotatable with said upper and lower portions when said clutch portions of said collar have been raised to mesh with the clutch portion of said slide member.

4. The combination of a string of drill pipe, a jar release device including a housing having an arbor and a movable arbor detention device therein, said housing having a cylindrical inner surface and said detention device having a cylindrical exterior surface engaging the cylindrical inner surface of the housing, and means shiftable axially of said housing and engaging said arbor detention device for adjusting the arbor detention device axially of the housing.

5. The combination of a string of drill pipe, a jar release device including a housing having an arbor and a movable arbor detention device therein, said arbor detention device including a resilient portion, said housing having a cylindrical inner surface of uniform diameter and the resilient portion of said arbor detention device having a cylindrical exterior surface engaging the cylindrical inner surface of the housing, whereby the detention device may be axially moved within the housing while its diameter remains constant, and means shiftable axially of said housing for adjusting the arbor detention device axially along the housing.

6. The combination of a string of drill pipe, a jar release device including a housing having an arbor and a unitary one piece arbor detention device movable therein, said housing having a cylindrical inner surface of uniform diameter and the resilient portion of said arbor detention device having a cylindrical exterior surface engaging the said cylindrical inner surface of the housing, and an adjusting device connecting said drill pipe and said jar housing, said adjusting device including means whereby rotation of said drill pipe will rotate said jar release device and selective means operable by said drill pipe to move said detention device axially within said housing.

7. The combination of a string of drill pipe, a jar release device including a housing having an arbor and a unitary one piece arbor detention device therein which is mounted to move axially in said housing, said housing having a cylindrical inner surface of uniform diameter and the resilient portion of said arbor detention device having a cylindrical exterior surface engaging the said cylindrical inner surface of the housing, said adjusting device including two rotatably mounted portions, clutch means selectively connecting said two portions, said adjusting device including means operable upon disengagement of said clutch means and upon rotation of one of said portions of said adjusting device to rotate said detention device and move it axially relative to said jar housing.

8. The combination of a string of drill pipe, a jar release device including a housing having an arbor and a unitary one piece arbor detention device therein which is shiftably mounted to move axially in said housing, said housing having a cylindrical inner surface of uniform diameter and the resilient portion of said arbor detention device having a cylindrical exterior surface engaging the

said cylindrical inner surface of the housing, an adjusting device, said adjusting device including two portions, clutch means for selectively connecting said two portions for rotative movement, said adjusting device including means operable upon disengagement of said clutch means and upon rotation of one of said portions to shift said detention device axially relative to said jar housing.

5 10. In combination with a string of drill pipe and a jar release device including a housing having an arbor and a unitary one piece arbor detention device movable therein, said housing having a cylindrical inner surface of uniform diameter and the resilient portion of said arbor detention device having a cylindrical exterior surface engaging the said cylindrical inner surface of the housing, an adjusting device connecting said drill pipe and said jar housing, said adjusting device including means operable upon rotation of said drill pipe to rotate said jar release device and selective means operable at the will of the operator to move said detention device axially within said housing.

15 10. The combination of a string of drill pipe, a jar release device including a housing having an arbor and a unitary one piece arbor detention device movable therein, said housing having a cylindrical inner surface of uniform diameter and the resilient portion of said arbor detention device having a cylindrical exterior surface engaging the said cylindrical inner surface of the housing, and an adjusting device connecting said drill pipe and said jar housing, said adjusting device including means to rotate said jar release device and selective means operable at the will of the operator to move said detention device axially within said housing.

20 11. The combination of a string of drill pipe, a jar release device including a housing having an arbor and a unitary one piece arbor detention device mounted to move axially in said housing, said housing having a cylindrical inner surface of uniform diameter and the resilient portion of said arbor detention device having a cylindrical

exterior surface engaging the said cylindrical inner surface of the housing, and an adjusting device connecting said drill pipe and said jar housing, said adjusting device including means operable at will to selectively rotate said jar housing with said drill pipe or to rotate said detention device and move it axially relative to said jar housing.

25 12. In combination with a jar release device including a housing having an arbor and a unitary one piece arbor detention device movably mounted therein, said housing having a cylindrical inner surface of uniform diameter and the resilient portion of said arbor detention device having a cylindrical exterior surface engaging the said cylindrical inner surface of the housing, an adjusting device secured at one end to said jar housing and at the opposite end to a string of drill pipe, said adjusting device including a lower portion and an upper portion, clutch means connecting said portions for rotative movement, said adjusting device including means whereby upon disengagement of said clutch means and upon rotation of one portion of said adjusting device said detention device will be moved axially in said jar housing.

30 13. In combination with a string of drill pipe and a jar release device including a housing having an arbor and a unitary one piece arbor detention device therein which is rotatable relative to said housing and when so rotated moves axially in said housing, said housing having a cylindrical inner surface of uniform diameter and the resilient portion of said arbor detention device having a cylindrical exterior surface engaging the said cylindrical inner surface of the housing, an adjusting device, said adjusting device including a lower portion and an upper portion, clutch means connecting said two portions for rotative disengagement of said clutch means and upon rotation of said upper portion of said adjusting device said detention device will be rotated and moved axially relative to said jar housing.

35 EDWARD F. RAYMOND.
